UNITED STATES PATENT OFFICE.

AUGUST KAMPFE, OF CLEVELAND, OHIO.

SAFETY DEVICE FOR ELEVATORS.

980,284.

Specification of Letters Patent. Patented Jan. 3, 1911.

Application filed September 24, 1910. Serial No. 583,595.

To all whom it may concern:

Be it known that I, AUGUST KAMPFE, a citizen of the United States, residing at Cleveland, in the county of Cuyahoga and State of Ohio, have invented certain new and useful Improvements in Safety Devices for Elevators, of which the following is a specification.

My invention relates to an improvement 10 in safety devices for elevators, and consists particularly in an improvement upon the device patented by me December 21, 1909, and numbered 943,939.

In the said device I have a construction 15 adapted to lock an elevator at a landing in such manner that the elevator cannot move up or down until the gate has been closed and the locking mechanism thereby released, and said device comprises a gate with a rack 20 R on its lower edge engaged by a pinion P upon a screw shaft S fixed in a box C at the landing. Upon said screw there is a cross-bar B adapted to run thereon like a nut and having a bolt 4 at each end adapted to be 25 thrust into holes in the bottom E of the car, so that when a landing is reached and the door is opened, as usual, the movement of the door causes the screw to rotate and to carry the bolts inward into said holes, thus 30 locking the elevator. The foregoing construction, however, required something more to make it complete because if the operator should turn on the power before he closed his door and while the bolts were still in 35 engagement excessive strains would come on the bolts and something would be liable to be broken. Hence I have devised means which will prevent the turning on of the power, whether it be hydraulic, electric or other power, before the door is closed and the bolts are thereby withdrawn.

The improvement herein therefore consists in mechanism which will accomplish this latter object, as will presently appear 45 and as is set forth in the claims.

Now, referring to the drawings, Figure 1 is a sectional elevation of an elevator construction showing a landing and a car at the landing in locked position. Fig. 2 is an 50 elevation in section of the same parts from a different point of view as hereinafter described. Fig. 3 is a plan view of the mechanism in one of its forms, and Fig. 4 is a perspective view of a modification thereof.

Having reference to the parts in the said patent, E represents the floor of the elevator

carriage or car and G the gate therein adapted to slide back and forth as usual and provided with a rack R at its bottom. The said rack is engaged by a pinion P upon a screw threaded shaft S fixed in a suitable box C in the landing and in the side of which box the bolts 4 are mounted.

L represents the power controlling lever adapted to be operated as such levers usually are and which governs the power by which the elevator is operated. In this case also as in my former construction, the elevator man has to do simply with the operating lever L and the gate G, and the mechanism for locking the said lever to prevent operation while the gate is open is governed from the gate through the bolts 4. One form of such mechanism is seen in Figs. 1, 2 and 3, and another and possibly a more simple form in Fig. 4. Thus, referring first to Fig. 4, A represents an arm pivoted at a at its lower portion in the bottom of the car and extending beneath its pivot in right angled or crank like formation in this instance to bring it into contact relation with one of the locking bolts 4, a spiral or equivalent spring serving to normally press against the lower end of said arm or lever and throw it out of contact at the top with the operating lever L. The said arm A has a right angled portion at its top provided with an open slot a' adapted to come astride of the lever L and when thus positioned to lock the lever against operation, the pivot a and its bearings at that point being of such strength as to hold the lever A in rigid position edge-wise, thus also making it firm as a grip for lever L as indicated in Fig. 3. It follows, of course, that when the bolt 4 is thrust into 90 engagement with the car through the bore or hole d in the car bottom the bolt 4 will press against the lower end of arm A and force its upper end into locking engagement with lever L. On the other hand when the said bolt is withdrawn by closing the door the spring b comes into action and throws the said arm A back out of engaging relations with lever L, thus liberating said lever for operation as ordinarily. The same general principle obtains in the other form of this device shown in Figs. 1, 2 and 3, excepting that in this form the bolt 4 engages the short arm of a crank lever 8 which has a spring 9 connected with the longer end thereof, and a link 10 connects between the said long end and the lower end of the arm A. Spring 105

9 is a retracting spring in this instance rather than a pushing spring, as in Fig. 4, but any suitable spring and intervening mechanism between bolt 4 and the lower end of arm A may be employed that will serve the purpose.

What I claim is:

1. Mechanism adapted to lock an elevator car at a landing comprising a carriage and a gate and a lever to control the power, in combination with means to prevent the operation of said lever while the gate remains open, said means having automatic operating connection with the mechanism locking the elevator carriage.
2. In elevators, a car and elevator gate and mechanism adapted to lock the car at a landing controlled by said gate, the same comprising locking bolts actuated from the gate, in combination with a power controlling lever, and means operatively engaged by one of said bolts adapted to lock said lever against operation while the elevator gate is open.

3. An elevator carriage and gate, a bolt to lock the carriage at a landing having controlling connection with the bottom of the door, in combination with a power lever and means to lock said lever and prevent operation thereof while the gate is open comprising a pivoted arm adapted to engage the said lever and operating connections between the said arm and said bolt.

4. An elevator carriage and gate and a landing, and a device comprising locking bolts adapted to hold said carriage at said landing when the gate is open, in combination with a lever to turn on the power, and means operatively engaged by one of said bolts adapted to lock said lever when the gate is open and prevent the lever from being operated.

In testimony whereof I affix my signature in the presence of two witnesses.

AUGUST KAMPFE.
